TREATMENT OF INNER SURFACES OF
ARCUATE TUBES

Roman Tettke, Sr., Rutherford, N.J., assignor to Bendix Aviation Corporation, Teterboro, N.J., a corporation of Delaware

Application April 20, 1956, Serial No. 579,611

4 Claims. (Cl. 51—58)

This invention relates to treatment of the inner surfaces of arcuate tubes, especially inclinometer tubes, and among its objects are the provision of improved methods and apparatus for reducing irregularities and smoothing the inner surface walls of such tubes.

Ball type inclinometer tubes comprise a glass tube bent in an arc and a ball which rolls therein. Such devices are used in a wide variety of indicator instruments, such as turn and bank indicators in aircraft, trim indicators on ships, and others.

It is essential in devices having inclinometer tubes, that the interior surface of the tube over which the ball rolls be perfectly smooth, so that a reading taken from the instrument will be an accurate indication of the attitude of the craft in which the instrument is incorporated. Small lumps, or a slight unevenness in the interior wall surface of the tube cause inaccurate readings. Such defects increase the friction between the rolling ball and the tube; they become more pronounced as angular lags are formed and, as a consequence, are the cause for inaccurate indications.

Defects of this nature are usually formed while the tube is being bent. The heating and bending process to which the tube is subjected, causes small irregularities in the tube wall. These defects are caused by, among other things, uneven temperatures, or small differences in the tube wall. They alter the effective radius over which the ball rolls and produce discrepancies in readings indicated by the ball.

The foregoing objects, as well as additional and more specific objects and advantages of this invention, will appear more fully hereinafter from a consideration of the detailed description which follows, taken together with the accompanying drawings wherein the invention is illustrated.

Fig. 1 is an elevational view of a fire bent inclinometer tube preparatory to the lapping operation;

Fig. 2 is a view of the lapping slug;

Fig. 3 shows the inclinometer tube mounted to a rocking machine; and

Fig. 4 shows the processed tube after the lapping operation.

In the drawings there is shown in Fig. 1 an inclinometer tube 1, formed in the usual manner, as by fire bending over a form to a predetermined radius. Evidences of irregularities, such as lumps, and other unevennesses in the interior wall surface of the tube are tested for by observing the actions of the conventional rolling ball used in such tubes. Irregularities are noted by stopping, slowing down and other irregular actions of the ball as it is caused to roll from one end of the tube to the other.

Assuming evidences of such irregularities to have been found, these are cured by a lapping process. To this end a short slug 2, accurately bent to the radius of the inside of the tube is placed within the tube together with a solution of a suitable abrasive material such as silicon

2

carbide grains or other suitable compound. Sealing corks 3 are plugged in both ends of the tube. The latter is then mounted to a suitable motor driven rocking machine 4. The rocking machine operates to rock the tube first in one direction and then in the other, as indicated by the dotted lines in Fig. 3, so as to cause the slug 2 to travel back and forth from one end of the tube 3 to the other, the stroke of the rocking machine being properly adjusted to this end.

10 Movement of the slug 2 together with the lapping solution during this rocking operation causes the high spots and other irregularities on the inner surface of the tube to be ground down to a desired smoothness.

The tube is tested from time to time as to the effects of the lapping operation. This is done by first removing the slug 2 and washing out the contents. The conventional ball used in such tubes is then inserted and caused to roll back and forth, its actions being observed as it rolls. After the lapping operation has proceeded for a short time, high spots partially ground down in the lapping process are visibly indicated.

15 The lapping compound used in the final stages of the lapping operation is a finishing compound of a relatively finer grain composition than that used in the initial part 20 of the operation. The finishing compound serves to provide a final highly accurate uniformly smooth curved inner surface to the tube.

The slug 2 may be formed of copper and of a material 30 which is not only heavy but is also relatively soft. The lapping compound of silicon carbide grains has a tendency to adhere to the surface of the copper slug because of the particular qualities thereof, whereby the lapping operation is materially promoted. The ends of the copper slug

35 are rounded as indicated at 5 and this is desirable as the lapping compound will tend to accumulate in the space between the tube and the rounded end surface of the slug. This permits the lapping compound to better attack the wall of the tube as the copper slug pushes the compound back and forth and weighs upon it during the 40 lapping operation.

After examination has revealed the irregularities in the inner surface of the tube to have been removed, the tube is washed out. The conventional ball 6, which may be

45 formed of tungsten carbide, is inserted in the tube. The ends of the tube are then sealed, as at 7, in the usual manner, and the conventional expansion reservoir 8 is attached. The customary damping fluid is added and the ball 6 will now roll smoothly over the lapped inner 50 surface of the tube 1 without the heretofore noted irregular actions. Moreover, the added fluid by wetting the lapped surface of the tube 1 renders invisible to the eye of the viewer the lapped surface of the inner wall of the tube and causes the ball to become sharply visible through 55 the glass of the tube.

While an embodiment of the invention has been illustrated and described in detail, it is to be expressly understood that the invention is not limited thereto. Various changes can be made in the design and arrangement of

60 the parts without departing from the spirit and scope of the invention, as the same will now be understood by those skilled in the art; and it is my intent, therefore, to claim the invention not only in the form shown and described, but also in all such forms and modifications there-

65 of as may reasonably be construed to be within the spirit of the invention and the scope of the appended claims.

I claim:

1. The method of grinding down to a smooth surface high spots in an inclinometer tube having a predetermined radius, comprising testing the tube for evidences of high spots, performing a slug of copper to a

radius accurately conforming to that of the inner wall of the tube for sliding action within the tube, inserting the slug together with a lapping compound solution in the tube, sealing the ends of the tube, rocking the tube back and forth to accordingly slide the slug and lapping solution in the tube.

2. In the method as in claim 1, wherein the slug and lapping compound solution are cleaned out of the tube from time to time and the tube is tested for evidences of the continued existence of high spots.

3. A method of lapping the inner surface wall of a curved glass tube, comprising the steps of preforming an elongated copper slug to a radius accurately conforming to that of the inner wall of the tube and with rounded ends, inserting the slug together with a lapping compound solution including silicon carbide grains in the tube, the silicon carbide grains tending to adhere to the copper slug and accumulating between the rounded end surface of the slug and the inner surface of the tube, and sliding the copper slug and lapping compound back and forth in the tube so as to lap the inner surface wall of the tube. 20

4. In lapping apparatus for lapping down to a smooth

finish high spots in the inner wall surface of an arcuate glass tube having a predetermined radius, a copper slug slidably mounted in the tube and being relatively smaller than the length of the tube and preformed to a radius accurately conforming to that of the inner wall of the tube, a lapping compound solution in the tube, and the copper slug having rounded ends to enable accumulations of lapping compound thereunder when inserted with said compound in said tube.
